ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

ATTACHMENT FOR T-SQUARES.

1,231,120.

Specification of Letters Patent. Patented June 26, 1917.

Application filed November 4, 1915. Serial No. 59,533.

To all whom it may concern:

Be it known that I, ERNEST J. BRASSEUR, a citizen of the United States, residing at Chicago, in the county of Cook and State of Illinois, have invented certain new and useful Improvements in Attachments for T-Squares, of which the following is a specification.

My invention relates to improved stops 10 or gages to be detachably and slidably secured to the blade of a T square, or a rule or the like. The device comprises a frame member within which is pivoted a lever, the lever being spring-pressed into upper position. When the device is placed transversely across the blade of the T square and the lever depressed, a shoulder on the bottom face of the lever adjacent the pivoted end thereof, will be positioned immediately beyond 15 one edge of the T square blade, and a corresponding shoulder on the bottom face of the frame, toward the opposite end of the same, will be positioned just beyond the opposite edge of the T square blade. Upon 20 releasing the lever, the spring will move the same, so that the T square blade will be quite firmly clamped between the two shoulders referred to, it being understood that the device is made to fit upon a T square blade 25 having a known width. When the stop is positioned at any desired point on the T square blade, it extends slightly beyond the two edges of the blade, and either of its side surfaces may be used for a starting and 30 stopping point for a pencil or pen in drawing lines on a surface underneath the T square blade.

My device is particularly applicable for use upon a T square when ruling lines upon 35 a stencil-sheet. In this case it may be desired to rule lines of a certain length at certain points upon the sheet which is readily accomplished by positioning two of the stops at desired points upon the T square 40 blade to form the starting and stopping points for the lines. This enables such lines to be ruled very quickly without the danger of the lines extending too far in either direction which is particularly to be avoided 45 in making stencil-sheets, since erasures can not readily be made. It is, of course, obvious that my improved stops may also advantageously be used in the same manner 50 when lines are to be drawn upon drawing paper or other substance, and also that it is

not essential for the stops to be used in pairs.

The object of my invention accordingly is to produce an improved stop of the character briefly described, having the advantages and constructional features hereinafter more fully set forth.

In order that a clearer understanding of my invention may be had, attention is hereby directed to the accompanying drawings forming part of this specification and illustrating the preferred form of my invention. In the drawings, Figure 1 represents a plan view of a T square, having a pair of my improved stops clamped thereon, Fig. 2 is a top plan view of one of the clamps on an enlarged scale, Fig. 3 is a vertical longitudinal section of the same taken on line 3-3 of Fig. 2, Fig. 4 is a bottom plan view, and Fig. 5 is a side elevation of the same.

Referring to the drawings, the stops 1, 1^a are represented as clamped upon the face of the blade 2 of a T square, the inner faces 3, 3^a of the stops serving as starting and stopping points for a pencil or pen forming ruled lines along the edge of the T square blade. Each stop is formed of a body having vertical side walls 4, 4 a top portion 5, a rear vertical wall 6 and a horizontal bottom portion 7 at the end opposite to the vertical rear wall 6. The frame is thus a hollow body, having the lever 8 extending therethrough, pivoted at one end on a pin 9, mounted between inwardly extending lugs 10, formed on the interior of side walls 4. The lever is bent upwardly, as is shown at 11, toward its opposite end, and is provided with an enlarged flat end portion 12, which serves as a thumb piece or handle for manipulating the same. A coiled spring 13 extends between the bottom horizontal portion 7 and the thumb piece 12, thus normally pressing the lever upward into contact with a shoulder or rib 14 formed at the under side of the forward edge of the top portion 5 of the frame, considering the vertical wall 6 of the frame as the rear end of the same.

It is to be understood that the body of the stop is an integral construction, which preferably includes the top 5 and the rear vertical wall 6, these portions of the frame, however, not being essential to the operation of the device. The side walls 4 are reduced in height, toward the forward end of the same, the upper surfaces of these walls descending

along the slanting line 15 to form the portions 16 of reduced height, these forward side portions being connected by the forward wall 17 of the same height, forward and rear walls 17 and 6 preferably being curved as shown. Forward walls 16 and 17 of reduced height form a seat or stop for the thumb piece 12 when the latter is depressed, the lever thus being free to move between the shoulder 14 and the upper surfaces of front walls 16 and 17.

The bottom surfaces of the side walls 4 are cut away slightly, to form shoulders 18 which may be practically in line with the rear edge of the bottom horizontal portion 7 of the frame as shown. The bottom surface of the lever is provided with a similar shoulder shown at 19 at a point slightly forward of the pivot 9. The distance between shoulders 18 and 19, when the lever is in the intermediate position shown in Fig. 3, is equal to the width of the blade of the T square. Accordingly, to clamp a stop upon the T square blade it is only necessary to depress thumb piece 12 against its seat 17, position the blade 2 between shoulders 18 and 19, and release pressure upon thumb piece 12, whereupon the tendency of the lever to rise due to the pressure of spring 13 clamps the blade firmly between shoulders 18 and 19, as is shown in Fig. 3. A stop can readily be unclamped by depressing thumb piece 12, to permit the stop to be slid along the blade into any desired new position.

35 The side walls of the stop are cut away somewhat on their bottom surfaces, as is shown at 20, from a point somewhat to the rear of shoulder 18 to a point slightly to the rear of shoulder 19 on lever 8.

40 It is obvious that my invention is not strictly limited to the exact form of construction described, the form particularly described, however, being preferred as embodying the most effective operation and attractive appearance. It is obvious that the stops described may be readily clamped to and removed from T square blades or rules without marring the surfaces of the latter in the least.

45 Having now particularly described my invention, what I claim and desire to protect by Letters Patent is as follows:

50 1. A detachable stop, adapted to be slidably secured across the blade of a T square or rule, comprising a frame having side portions, and a horizontal portion at one end, a lever pivoted at one of its ends between said side portions, adjacent the end of said frame opposite to said horizontal portion, the free

end of said lever extending above said horizontal portion, and a spring between said horizontal portion and the free end of the lever, to press the latter upwardly, said lever having a transverse shoulder on its under side, adjacent the pivot thereof, and said frame having a transverse shoulder on its under side, in alinement with the shoulder on said lever when the latter is in depressed position, said shoulders being adapted to clamp the opposite edges of the blade, substantially as set forth.

2. A detachable stop, adapted to be slidably secured across the blade of a T square or rule, comprising a frame having side portions, a lever pivoted at one of its ends between said side portions, adjacent one end of the frame, and spring means mounted to press the free end of said lever upwardly, between said side portions, said lever having a transverse shoulder on its under side, adjacent the pivot thereof, and said frame having a transverse shoulder on its under side under said lever, in alinement with the shoulder on said lever when the latter is in depressed position, said shoulders being adapted to clamp the opposite edges of the blade when said lever is depressed, substantially as set forth.

3. A detachable stop, adapted to be slidably secured across the blade of a T square or rule comprising a frame having vertical side walls, a horizontal bottom portion adjacent one end, and a top portion extending from a point intermediate the ends toward the end opposite to that at which the bottom portion is located, a lever pivoted at one of its ends between said side walls, adjacent the end of said frame opposite to said horizontal bottom portion, the free end of said lever extending above said bottom portion and being provided with a thumb piece, and a coiled spring between said thumb piece and said bottom portion, to press the lever upwardly into contact with said top portion, said lever having a shoulder on its under side, adjacent the pivot thereof, and said frame having a shoulder on its under side, in alinement with the shoulder on said lever when the latter is in depressed position, said shoulders being adapted to clamp the opposite edges of the blade, substantially as set forth.

This specification signed and witnessed this 30th day of October, 1915.

ERNEST J. BRASSEUR.
